CLAIM

The ornamental design for a rabbit litter box as shown and described.

DESCRIPTION

FIG. 1 is an isometric view of a rabbit litter box in accordance with the present application.

FIG. 2 is a front view of the rabbit litter box.

FIG. 3 is a back view of the rabbit litter box.

FIG. 4 is a top view of the rabbit litter box.

FIG. 5 is a bottom view of the rabbit litter box.

FIG. 6 is an exploded view of the rabbit litter box; and, FIG. 7 is an alternate exploded view of the rabbit litter box. The broken lines illustrate portions of the rabbit litter box that form no part of the claimed design. The long-short dashed broken lines represent assembly lead lines for exploded views and form no part of the claimed design.
